US00D906301S

(12) **United States Design Patent** (10) **Patent No.:** **US D906,301 S**
(45) **Date of Patent:** **** Dec. 29, 2020**

(54) **TELEVISION RECEIVER**

- (71) Applicant: **Samsung Electronics Co., Ltd.**, Suwon-si (KR)
- (72) Inventors: **Bo-Kyung Seong**, Daejeon (KR); **Gyoosang Choi**, Suwon-si (KR)
- (73) Assignee: **SAMSUNG ELECTRONICS CO., LTD.**, Suwon-si (KR)

(**) Term: **15 Years**

(21) Appl. No.: **29/686,622**

(22) Filed: **Apr. 5, 2019**

(30) **Foreign Application Priority Data**

- Oct. 12, 2018 (KR) 30-2018-0047020
- (51) **LOC (12) Cl.** **14-03**

(57) **CLAIM**

The ornamental design for a television receiver, as shown and described.

DESCRIPTION

FIG. 1 is a front perspective view of a television receiver showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is an enlarged view of the encircled portion in FIG. 8.

The dashed broken lines in the figures depict portions of the television receiver that form no part of the claimed design. The dot-dot-dash broken lines encircling portions of the claimed design that are illustrated in enlargements form no part of the claimed design.

1 Claim, 9 Drawing Sheets
